UNITED STATES PATENT OFFICE.

ROBERT GEORGE ELLIOTT, OF SOUTH BARTONVILLE, ILLINOIS.

MECHANICAL MOVEMENT.

1,162,464.

Specification of Letters Patent. Patented Nov. 30, 1915.

Application filed April 24, 1913. Serial No. 763,424.

To all whom it may concern:

Be it known that I, ROBERT G. ELLIOTT, citizen of the United States, residing at South Bartonville, in the county of Peoria and State of Illinois, have invented certain new and useful Improvements in Mechanical Movements; and I do hereby declare that the following is a full, clear, and exact description of the invention, which will enable others skilled in the art to which it appertains to make and use the same.

This invention relates to a mechanical movement.

The movement is particularly adapted to the operation of pumps, air pumps or air compressors, and other mechanisms.

It relates particularly to an eccentrically mounted disk or wheel and a reciprocating element operated by it, the line of movement of said element being in line with the axis of rotation of said disk or wheel but perpendicular thereto.

The main object of the invention is to provide a peculiarly constructed mechanism, including an eccentric for imparting a reciprocating movement to an element, whereby by reaction of stored energy through said element will be prevented from rotating the latter.

Another object is to provide a mechanical movement particularly adapted to air compressors or air pumps and requiring but little power for the operation of said compressor or pump, the mechanism including means to prevent back pressure reacting upon the power transmitting portion.

To the end that the invention may be fully understood I have provided the accompanying drawing, in which,

Figure 1 is an elevation of my mechanical movement as applied to an air compressor. Fig. 2 is a transverse sectional elevation of a part of the same, and Fig. 3 is a horizontal section of the frame shown in Fig. 1 on line X-X, showing certain operating parts.

A represents any suitable framing having journaled at its upper end a shaft B to which is secured by means of a key C, for example, a wheel or disk D preferably circular in form and preferably provided with

rims E the particular structure and purpose of which will appear presently.

F is the cylinder of an air compressor, G its piston, and H a piston rod. The longest axis of the piston rod is in line with, and perpendicular to, and would pass through the axis of rotation of the shaft B. At its end it carries, as a preferred structure, a member J to opposite sides of which are pivoted a cross arm L by means of a pin M which passes through said member J and extends some distance beyond the arms L at each side and into the guideways N, Fig. 2, said guideways being shown also in broken lines in Fig. 1. The cross arms are adapted to rock upon the pin M and between their ends are rollers O which bear upon the periphery of the wheel or disk D as shown in full lines in Fig. 1.

The member J has two vertical extensions P to which a pair of links Q are pivoted at one end the other ends of the latter carrying rollers R. The rims E of the disk or wheel D, as shown in Fig. 2, are formed by providing an annular flange at each side of the wheel. These project from each side face of the wheel and one of the rollers R just described engages each.

It is observed that in the rotation of the disk or wheel on its axis, which is the shaft B, its edge when moving in a downward direction will force the piston G downward, while in the raising movement through the rims E, the rollers R and the links Q, the piston will be raised.

It is customary to make application of power in air compressors and other forms of devices through a crank arm or from a crank pin spaced from and having an orbital movement around the axis of rotation of said crank. This results in a counter-force or a force opposite in direction to that from which the power comes since the axis of the reciprocating member receiving this power always lies at one side of the said axis of rotation, except for a single moment when the axes of the two are in line. This is a great disadvantage in many forms of devices and especially in the operation of an air compressor or air pump where the

2
back pressure upon the crank arm in opposition to the power applied is considerable. For this reason a piston for a compressor must be very small in area in order that it 5 can be operated properly. Now, by keeping the axis of the piston rod of the compressor in line with the axis of rotation of the disk D the back pressure can have no effect whatever upon the wheel or disk in tending to rotate it in a contrary direction. In my structure the two rollers O are employed in order 10 to equalize the pressure by providing a point of contact at each side of the central line of the piston rod and also side strains are 15 more readily eliminated though a single roller might be used perhaps if desired where power is of no moment. The use of the single roller, however, could not well be employed in a hand operated machine. The 20 arms L which carry these rollers are pivoted so that said rollers may adapt themselves to the angularity of the edge of the wheel or disk which is ever changing.

The pin M is a guiding member moving 25 within the guideways N, lateral strain on the piston being practically eliminated.

It is clear that the position of the wheel or disk D in its rotation, with regard to the power applied, is of no moment since in any 30 part of such rotation the cross arms L adapt themselves to it, the piston rod being always in line with the axis of the shaft B.

It has been found that by such a structure, a piston several inches in diameter for 35 an air compressor can be readily operated with but little power, and that rotation can even be imparted by hand to the disk or wheel which would not be possible if the line of back pressure were elsewhere than 40 always through the axis of the rotation of the said disk or wheel. As a proof of this the piston will remain in any position left without any retrograde movement so that there will be but little expenditure of power 45 as compared with a device where the piston rod is operated through a lever-arm, other conditions named herein being equal.

The structures with regard to arrangement of the various parts of my mechanical 50 movement or of any of the parts that receive the pressure of the disk or wheel may be varied at will, of course, without departing from the spirit and intent of the invention.

55 Having described my invention, I claim:—

1. In combination, an eccentrically mounted rotatable disk or wheel, a member adapted to have a reciprocating motion, the said line of movement of the member and the 60 said axis of rotation of the disk or wheel being perpendicular to one another, said axis of rotation of the disk or wheel and the longitudinal axis of the member lying in the same plane, a member mounted on

the first said member adapted for free piv- 65 otal movement with respect thereto and including a part at each side of the axis of movement of the member on which it is mounted and having engagement with the said disk or wheel and reciprocated by it. 70

2. A mechanical movement comprising an eccentrically mounted rotatable disk or wheel and a member adapted to reciprocate, the line of movement of the latter and the axis of rotation of the disk or wheel lying 75 substantially perpendicular to one another, the axis of the disk or wheel and the longitudinal axis of the member lying in the same plane, the member adapted to receive motion from the said disk or wheel, and a 80 cross-head pivotally mounted upon the said reciprocating member including an extension at opposite sides of the said line of movement of the member, and an anti-friction device on each of the extensions adapted to bear upon the periphery of the said disk or wheel. 85

3. In a mechanical movement, means for imparting a reciprocating movement to a member in a single given direction which 90 comprises an eccentrically mounted rotatable disk or wheel including an extended rim perpendicular to its plane of rotation, a reciprocating member having its axis lying perpendicular to the axis of rotation of the 95 wheel or disk and adapted to receive motion from said wheel or disk, the axis of rotation and the axis of said reciprocating member cutting one another, and a cross head pivotally mounted upon the said reciprocating member and including a friction member at each end adapted to bear upon the outer periphery of the said disk or wheel, and a member carried by the reciprocating member and engaging the inner 100 surface of said disk or wheel.

4. In combination, a member to which a reciprocating motion is to be imparted in a direct line, a support, a member mounted to rotate on the support and having a circular 11 periphery and an extended rim, its axis of rotation being eccentric to its said periphery, a reciprocating member interposed between the first said member and the said axis of rotation, a guide with which said reciprocating member engages, and a member pivoted relative to the reciprocating member and including a part extending at each side of the line of movement of the latter and engaging the periphery of the first said 1 member.

5. In combination, a member to which a reciprocating motion is to be imparted in a direct line, a support, a member mounted to rotate on the support and having a circular 1 periphery and an extended rim, its axis of rotation being eccentric to its said periphery, a reciprocating member interposed be-

tween the first said member and the said axis of rotation, a guide with which said reciprocating member engages, a member pivoted relative to the reciprocating member and including a part extending at each side of the line of movement of the latter and engaging the periphery of the first said member, and a part extended from the re-

ciprocating member and engaging the inner surface of the rim of said first member. 10
In testimony whereof I affix my signature, in presence of two witnesses.

ROBERT GEORGE ELLIOTT.
